UNITED STATES PATENT OFFICE.

RICHARD E. PEDIGO, OF LUCAS, IOWA.

CUT-OUT FOR RURAL TELEPHONES.

SPECIFICATION forming part of Letters Patent No. 772,327, dated October 11, 1904.

Application filed April 23, 1904. Serial No. 204,656. (No model.)

To all whom it may concern:

Be it known that I, RICHARD E. PEDIGO, a citizen of the United States, residing at Lucas, in the county of Lucas and State of Iowa, have 5 invented a new and useful Cut-Out for Rural Telephones, of which the following is a specification.

My object is to prevent the annoyances, dangers, accidents, and damages incident to 10 strokes of lightning following telephone line-wires to an instrument and an operator at the instrument.

My invention consists in the construction, arrangement, and combination of an automatic lightning-arrester and cut-out with the outside of a building and a telephone inside of 15 the building, as hereinafter set forth, pointed out in my claims, and illustrated in the accompanying drawings, in which—

20 Figure 1 shows a section of the wall of a building and my invention applied to the wall as required for practical use. Fig. 2 is a top view of the base upon which the operative devices are mounted and combined. Fig. 3 is a 25 transverse sectional view of the base, the binding-posts, comb protector-plates, a lever, and means for operating the lever from the inside of a building.

The numeral 10 designates a base made of 30 porcelain. It is preferably circular and has a flange 12 at its circumference. An oblong brass plate 13 is fixed on top of the base and triangular-shaped brass comb-plates 14 and 15 on top of the base contiguous to the parallel edges of the plate 13 by means of screws, as clearly shown in Fig. 2. A binding-post 16, adapted to serve as a bearer for a lever 17, fulcrumed to its top, is fixed on top of the plate 13 and to the base 10 by means of a 35 screw *b*, as shown in Fig. 3. A binding-post 18 is fixed on top of the plate 14 and the base 10 by a screw *b*, and a corresponding binding-post 19 is fixed on the plate 15 and the base 10 by a screw *b*. The posts 18 and 19 are 40 provided with contact-clips to coöperate with the switch-blade. A line-wire conductor 20 is fixed to the post 19 and a ground-wire 21 to the post 18. A telephone 22 is attached to the inside of the wall, as shown in Fig. 1,

and a wire 23 connected with the central binding-post 16 and a binding-post 24 on the telephone, and a wire 25 is connected with the binding-post 18 and a binding-post 26 on the telephone. A porcelain tube 27 is fixed in the wall and a stem 28 extended through it and 50 pivotally connected with the end of the long arm of the lever 17 and provided with a rubber button 29 on its free end for manually operating the lever as required to cut out the telephone from communication with the 55 line-wire 20 whenever desired by simply pressing the button 29 to place the short arm of the lever 17 in contact with the binding-post 18.

The base 10 is fixed to the outside of the 60 wall of a building by means of screws *c*, extended through apertures or in any suitable way.

Having thus set forth the purpose of my invention and the construction, arrangement, combination, and function of each part, the practical operation and utility thereof will be 65 readily understood by persons familiar with the art to which it pertains, and

What I claim as new, and desire to secure 70 by Letters Patent, is—

1. In a lightning-arrester and cut-out for 75 telephones, a porcelain base having a flange at its circumference, a brass plate fixed on its top and center, a binding-post fixed on top of 80 said plate and a lever fulcrumed to the top of the post, comb-plates fixed on the top of the base on the opposite sides of said fixed brass plate and binding-posts provided with contact-clips fixed on top of said comb-plates, a 85 stem pivoted to the long arm of said lever and provided with a rubber button on its end, arranged and combined to operate in the manner set forth for the purposes stated.

2. A lightning-arrester and cut-out for 90 telephones comprising a porcelain base having a flange at its circumference, a brass plate fixed on its top and center, a binding-post fixed on top of 95 said plate and a lever fulcrumed to the top of the post, comb-plates fixed on the top of the base on the opposite sides of said fixed brass plate and binding-posts provided with contact-clips fixed on top of said comb-plates,

a stem pivoted to the long arm of said lever and provided with a rubber button on its end, a line-wire connected with the right-hand binding-post, a ground-wire connected with the left-hand binding-post, a wire connected with the central post and a telephone and a wire connected with the left-hand binding-

post and the telephone, arranged and combined to operate in the manner set forth for the purposes stated.

RICHARD E. PEDIGO.
